CLAIM

The ornamental design for a display screen or portion thereof with transitional graphical user interface, as shown and described.

DESCRIPTION

FIG. 1 is a front view of a first image in a sequence for a display screen or portion thereof with transitional graphical user interface showing my new design; and, FIG. 2 is a front view of a second image thereof.

The appearance of the transitional image sequentially transitions between the images shown in FIGS. 1-2. The process or period in which one image transitions to another image forms no part of the claimed design.

The outer perimeter shown in broken lines in the figures illustrates a display screen or portion thereof and forms no part of the claimed design. The remaining broken lines in the figures illustrate portions of the graphical user interface that form no part of the claimed design.

1 Claim, 2 Drawing Sheets

FIG. 1

When you open Galaxy Z Flip, a screen with a 21:9 ratio like that of a movie screen unfolds before your eyes. It is perfect for watching contents. The user experience has also been intuitively refined based on the One UI concept for optimized use on a longer

FIG. 2

When you open Galaxy Z Flip, a screen with a 21:9 ratio like that of a movie screen unfolds before your eyes. It is perfect for watching contents. The user experience has also been intuitively refined based on the One UI concept for optimized use on a longer
